UNITED STATES PATENT OFFICE.

ALBERT L. BLACKMAN, OF NASHVILLE, TENNESSEE.

VESSEL FOR AERIAL NAVIGATION.

SPECIFICATION forming part of Letters Patent No. 259,464, dated June 13, 1882.

Application filed July 13, 1881. (No model.)

To all whom it may concern:

Be it known that I, ALBERT L. BLACKMAN, a citizen of the United States of America, residing at Nashville, in the county of Davidson 5 and State of Tennessee, have invented certain new and useful Improvements in Vessels for Aerial Navigation and Machinery for Actuating and Handling Aerial Vessels; and I do hereby declare the following to be a full, clear, 10 and exact description of the invention, such as will enable others skilled in the art to which it appertains to make and use the same, reference being had to the accompanying drawings, and to letters or figures of reference 15 marked thereon, which form a part or this specification.

My invention relates to certain improvements in vessels for aerial navigation, and in machinery for propelling and handling the 20 same; and it consists in securing a combined rubber-packed hinge arranged along the sides at the gunwales as well as on either side of the dome-ridge in the metal covering of vessels for aerial navigation, whereby the flexible cov- 25 ering of the gas-field of such vessels may move as on a hinge in expanding and collapsing without danger of cracking or otherwise injuring the metal.

It also consists in constructing the cabins, 30 engine, store, and other living and business rooms within the vessel in such a manner that by closing the doors and windows the air may be compressed within the vessel to any desired density for use in high altitudes, and also by 35 connecting said living-rooms and business-compartments with the outer air with pipes provided with automatic escape-valves arranged to relieve the internal pressure.

It also consists in carrying the steam-pipes 40 and smoke-stack through a fire-proof and heat-repellant chimney passing up through the gas-field of the vessel.

It consists, also, in connecting the several 45 gas-compartments with a gas-reservoir and gas-condensers by connecting-pipes provided with automatic as well as manual valves.

My invention further consists in arranging 50 dead-eyes in or near the bottom of the vessel, through which the anchor-cable may be paid out or hauled in over winches arranged in the vessel for that purpose; and, also, in arrang-

ing bull's-eyes for light adjusted in the cabin from above.

My invention also consists in simplifying the propelling machinery, so that the several side 55 and after screws may all be actuated simultaneously or each separately and changed to work upward, downward, forward, backward, or laterally at the will of the engineer, as well as in simplifying the machinery for changing 60 the position of the several screws.

It also consists in providing an automatic pendulum-lever attachment to the revolving cylinder-shafts which carry the side screws, by 65 and through which the direction of the side screws may be automatically changed to such a position as will best conduce to keep the vessel on a level keel.

It also consists in the manner of securing the plates of metal used for covering the ves- 70 sel to one another. All of which is more fully pointed out in the specification following, reference being had to the accompanying drawings.

Figure 1 is a side elevation of a complete 75 vessel in flight. Fig. 2 is a vertical longitudinal section of the same, showing the gas-condensers, gas-receivers, engine-room, engine, smoke-stack, cabin, general frame of the vessel, lines, cords, and bracings, as well as the loca- 80 tion of the after screw and its actuating-shaft. Fig. 3 is a plan of the same, showing the location and general arrangement of the actuating machinery and the side and rear screws. Fig. 4 is a plan of the cabin rearward and for- 85 ward passages. Fig. 5 is a plain cross-section of the vessel's cylinder. Fig. 6 is a cross-section of the vessel in the center, showing the steam and smoke pipes and casing, the side screws, the engine and engine-room, cabin, and 90 general supporting-braces. Fig. 7 is a frag- ment of the outer covering of the vessel, show- 95 ing the outside netting and the manner of joining the sheets of metal together and the adjustment of the rubber-packed hinge. Fig. 8 is a cross-section of a fragment of the outer cover of the vessel, as well as the rubber-packed hinge attached to the end of a cross-girder. Fig. 9 is a side elevation of a fragment 100 of the outer covering of the vessel, showing a side-wheel journal-bearing and the rubber-packed hinge. Fig. 10 is the side elevation of

the bearing for a side-screw shaft passing through the side of the vessel. Fig. 11 is a plan of the actuating machinery for aerial vessels, showing, besides the raising, lowering, 5 and propelling side screws, propelling, raising, lowering, and steering after screws, the propelling-shaft's gear for shifting the position of the several screws, and the adjusted pendulum-lever for keeping an even keel. Fig. 12 is a 10 plan of the shaft for carrying and mechanism for changing the position of the after screw, showing a sliding loop, corrugated on the inside, the universal joint, the reversing-gear, and screw. Fig. 13 is a side elevation of the same. 15 Fig. 14 is the termination of the rear shaft with an adjustment for changing the direction of the after screw. Fig. 15 is a plan of a fragment of the vessel's body, looking up from the bottom, showing the lookout-galleries. Fig. 20 16 is a cross-section of the body of the ship, showing the protruding lookout-galleries. Fig. 17 is an automatic pendulum-lever. Fig. 18 is a hand-lever.

The several letters of reference indicate 25 corresponding parts.

The general frame of the vessel comprehends the top cord or dome-ridge, A, keelson B, center cord, C, gunwales D D', thwarts E E', sub-gunwales F F', cross-girders c c c, &c., cross-girders i i i, &c., longitudinal cord G, stanchions H H H H H, &c., braces d d d, &c., cross-braces b b b, &c., ties h h h, &c., all preferably of steel tubing, and nodes a a'.

The dome-ridge A is in form a plane abruptly 35 curved to a central point aft and gradually drooped to a central point forward. It passes over from the stem to the stern of the vessel, and, being secured at its ends, forms the main upper support of the vessel.

The keelson B is of the same form as the dome-ridge A, but in a reverse position, secured by the ends in the nodes a a' fore and aft, and forms the main lower or under support of the vessel.

The center cord, C, is secured at the nodes a a' fore and aft, passing longitudinally through the vessel, becoming the main lateral support of the vessel. The two gunwales D D', identical in form with cords A and B, are secured 50 by the ends in the nodes a a' fore and aft and pass elliptically along the sides of the vessel on a plane with central cord, C, giving the vessel lateral diameter corresponding with the vertical diameter given by the dome-ridge A 55 and keelson B.

The thwarts E E' are inside of and run parallel with gunwales D D'. These thwarts are secured by the ends in the sides of the gunwales D D' forward, and, making abrupt curves inwardly, intersect and are by the ends secured to the central cord, C, aft.

The cord G passes longitudinally through the vessel from stem to stern vertically beneath cord C, intersects and is secured fore and aft 65 in the angles of keelson B.

The sub-gunwales F F' are curved similar to

thwarts E E', run parallel with but vertically below them on a plane with longitudinal cord G.

The cross-girders c c c, &c., intersect, lie 70 across, and are secured to the gunwales D D', thwarts E E', and central cord, C, furnishing the central lateral bracing for the vessel, the base of the gas-field, the ceiling of the cabin, and the supports for the pendent actuating 75 machinery.

The cross-girders i i i, &c., lie across, intersect with, and are secured to the sub-gunwales F F' and longitudinal cord G, forming the floor of the cabin and ceiling to the store, 80 freight, engine, and other rooms below. The keelson B is the basis of the lower floor.

The stanchions or vertical posts H H H H, &c., which intersect with and are secured to keelson B, cords G and C, and dome-ridge A, 85 form the main vertical supports, braces, and ties of the vessel.

The cross-girders c c c, &c., i i i, &c., and stanchions or posts H H H, &c., are arranged at such intervals as will best conduce to 90 strengthen the vessel and to add no unnecessary weight to be lifted.

The braces, cross-braces, and ties d, b, and h are arranged in such a manner as to securely tie and strengthen the several parts and bind 95 them firmly together.

The frame, as described, is secured at all of its several intersections in any substantial manner whereby great strength, combined with lightness, may be secured, and the whole 100 thoroughly braced throughout, as shown in the drawings.

Longitudinally the vessel is divided internally into gas-compartments by air and gas tight laterally-arranged bulk-heads j j j j, &c., 105 preferably of light metal of great tensile strength, of the full diameter of the vessel at the several points, the better to control inflation and to provide against accident from leaks, ruptures in the envelope, &c.

In the center of the vessel, between the lines marked x x, the gas-field comes down but to cord C, forward and aft of which points, with the exception of narrow passage-ways o o', to the machinery, &c., and through which gas-supply and gas-exhaust pipes n'' n'' are carried. The gas-field involves the entire area of the vessel.

The several gas-compartments are connected with a general gas-reservoir, l l', gas-condensers m m', and gas-generator k by means of a series of pipes, n n', arranged along the interior passages, o o', and each is supplied with an exhaust-pipe connected with a general exhaust-pipe, n''' n''', passing out at the stern of the 125 vessel, and each pipe is supplied with both an automatic valve and a valve to be operated by hand.

The entire vessel is incased or inclosed in a general envelope, K, preferably of thin steel 130 plates, riveted, welded, or soldered together, as shown in Fig. 7, and made perfectly air and

gas tight and fire and water proof, and constructed of material of sufficient tensile strength to sustain the required strain from inflation in high altitudes as well as the atmospheric pressure from without before inflation.

5 Ranging along the sides of the vessel at the gunwales D D', as well as along and on both sides of the dome-ridge A, from the angle forward to the angle aft, is a rubber-packed and perfectly air and gas tight armored hinge, I I I I, (see Fig. 9,) to enable the envelope of the body of the vessel to collapse or inflate without danger of cracking or breaking the metal at those otherwise stationary points.

15 In the immediate center of the vessel, passing out from the engine-room below up through the top, is a smoke and steam pipe chimney or well, J—a fire, gas, and water proof well-like passage—thoroughly ventilated, out through which the smoke and steam pipes are carried.

20 Inserted and secured in the sides of the vessel, in the region of cords G G', are pipe-journal boxes L' L', (see Figs. 9 and 10,) through which the revolving cylinder-shafts M M', 25 which carry the side screws, pass from the interior outward, and in which they take their outward bearings. p p' are dead-eyes in the hull of the vessel, through which the anchor-cables q q' pass from the interior of the vessel 30 outward. r r' are lookout-galleries protruding beyond the side of the hull of the vessel in such a manner that the vessel's side will not obstruct the downward or longitudinal view.

Internally the vessel is divided into a gas-35 field, as shown, engine-room, machinery-room, store and freight rooms, and a cabin, as follows:

40 Resting on the lower cord or keelson, B, sustained by braces, ties, and girders, is a substantial floor, s, preferably of metal, which forms the floor of the engine, store, and freight as well as machinery rooms. On this floor the gas-condensers m, gas-generators k, and gas-reservoirs l, water-tanks, coal-bunkers, 45 cable-winches, and anchors are located. Above this floor, on a line with cord G, is a second floor, preferably of metal, (see Fig. 4,) which becomes the cabin floor. On this floor are the offices, living-rooms, passage-ways forward and 50 aft, and from this floor the lookout-galleries protrude and the actuating machinery is arranged.

The gallery or passage-way o extends forward a short distance from the cabin under 55 cord C, to admit of visiting the pipes, cocks, and valves communicating with the gas-compartments, and for the passage of induct and educt pipes. The gallery or passage-way o' extends to the rear of the vessel to the point o'', to furnish means of communicating with the after screw and with the several gas-compartments and to furnish a passage for the revolving cylinder-shaft M', educt and induct pipes, as well 60 as the general exhaust-pipe 1.

65 The vessel is raised, propelled, and lowered by one, two, or more large screw-propellers, O

O', arranged in revolving cylinder-shafts M M', passing from the interior of the vessel out through the sides, and is propelled, steered, lowered, and raised by a large screw-propeller, O², secured in a revolving cylinder-shaft, M², passing from the interior out through the rear or stern of the vessel.

70 A description of the connections and mode of handling one of the side screws will serve 75 for all.

M is a cylinder-tube, of metal, secured in boxings L in the interior of the vessel and in a boxing, L', in the outer wall of the vessel, in which it revolves on its own axis as a journal, 80 carrying with it the rotating screw O, as herein-after shown. On the inboard end of the shaft M is secured a beveled spur, e, which meshes with a bevel-gear wheel, e', as herein-after described. On the outboard end of the 85 revolving cylinder M is a box or cross-tube head, t, provided with two journal-boxings, t' t'', into which are inserted the journals uu' on shaft P of the axle of the screw O.

On the shaft P is secured a beveled-gear 90 wheel, V, which meshes with beveled-gear wheel V' on the end of shaft Q.

Through the gear-wheel V motion is conveyed to the screw O by the beveled-gear wheel V', coming from the actuating-shaft R 95 through revolving shaft Q.

It will be observed that the axes and the impulse of the screws O are at right angles to the line of the revolving shaft, M, and that the line of motion is perpendicular therewith, so that 100 by turning the hollow shafts M on their own axes the impulse of the screws will carry the vessel upward, downward, forward—in short, in any desired direction. The shaft Q, in the meantime revolving on its own axis in journal-bearings within the cylinder M, conveys 105 through the beveled-gear wheels V' and V a rapid rotary motion to the screw O.

On the inboard end of the revolving shaft Q, which is also journaled in a boxing, 3, is 110 secured another beveled-gear wheel, 3', which meshes with a similarly-beveled gear-wheel, 3² or 3³, secured by a clutch and lever on the actuating-shaft R.

On each cylinder-shaft M is secured, within 115 the vessel, a collar or muff, w, having a protruding lever-arm, w', to which is journaled a lever-arm, w², that connects the collar w with a weighted pendulum, S, carrying a ball, S'.

The pendulum S is secured on a rocker-shaft, 120 w³, journaled at the ends and suspended near the side of the vessel about midway between the side screws, when two or more screws are used on the side, the object and purpose being that when the vessel deviates from a horizontal plane the pendulum, swinging to a perpendicular, acting through the lever-arms w' w², revolves the two cylinders M M, one down and its fellow up, thus changing the position or direction of the respective screws automatically, 125 130 as it were, so that one screw will pull downward and the other upward, whereby the ves-

sel is immediately brought to a level keel, when the pendulum will at once resume its normal position. These pendulums are arranged on both sides of the vessel, one between each set 5 or two screws adjusted on the same side.

O^2 is a stern propelling and steering screw of the same general form and material as the side screws, but differently mounted. The axis and impulse of after screw O^2 in its normal position are perpendicular with cylinder-shaft M^2 and actuating-shaft R , to which latter it is attached by a universal joint, 2, secured on the inner end of axle-shaft y of the screw, after it passes through its journal-box z , secured on the 10 periphery of an adjustable circular ring, disk, or sliding bed, $8'$. Screw O^2 is mounted to be thrown to the right or left, when desired, for steering or raising or lowering purposes by revolving the circular bed $8'$ on its axis, as herein- 15 shown, and through the universal joint 2 it is actuated in a position at right angles to its former position by the actuating-shaft R , which passes from the interior of the vessel out through cylinder-shaft M^2 , in which it has journal-bearings. 20

Cylinder M^2 has a beveled-gear band, 11, on the interior end, which meshes with beveled-gear wheel $11'$, to be referred to hereinafter. The outer end of this cylinder is provided with 25 a sliding collar or sleeve, 5, having a yoke-bow or branching arms, forming a looped strap, 6, which adjusts and works in longitudinal grooved ways 9 in the periphery of the elongated bow or yoke 7, which terminates the outer end of cylinder M^2 . Said looped strap has rack-teeth 10 on the inner edge of one side, which mesh with similar teeth on the periphery of the segment of circular disk or ring $8'$, which carries the after screw O^2 , and it revolves on its own axis, the same as cylinders 30 M M' , in journal-bearings L within the hull of the vessel, in the vessel's shell L'' , and in brackets L^3 , secured to the outside of the hull of the vessel, and carries within it the actuating-shaft R , terminating in a universal joint, 2. (See Figs. 11, 12, and 13.) 45

The loop-yoke 7, which terminates the outer end of cylinder M^2 , has within the jaws of the loop a circular recessed bearing, 8, in which 50 the circular ring, disk, or bed $8'$ is embedded and revolves on its own axis, actuated by the racked loop-strap 6 when it is desired to change the position and direction of impulse of the screw O^2 , and is channeled on the periphery 55 for guiding the loop-strap 6.

The circular disk or ring $8'$, embedded and revolving in the recess 8 in the loop-yoke 7, is provided with rack-teeth $7'$ on a segment of its periphery for meshing with the rack-teeth 60 10 in the strap-yoke or bow 6. It is also provided with a sleeve-journal-bearing, y' , in which the shaft, shank, or axle y of the after screw O^2 takes its bearings, is secured, and revolved. It is also cut away at the side opposite to the 65 journal-bearing y' to make space for the passage of the actuating-shaft R and to admit

of moving the ring or disk $8'$ without obstruction.

The sliding sleeve or collar 5 has two gibs, 5', protruding from opposite sides, and these 70 gibs journal in a cross-head, 5², carried on the end of piston 5³, secured at the other end to and handled by a hand-lever, 5⁴. (See Figs. 11, 12, 13, and 18.) The whole is arranged and designed to change the position of the after 75 screw, as follows: By drawing the lever in-board the sliding collar 5 is drawn up on the cylinder M^2 , carrying with it the yoke-bow 6, as shown by the dotted lines in Fig. 12, the rack-teeth 10 therein meshing with rack-teeth 7' on 80 the ring or disk $8'$ turns ring $8'$ on its axis, carrying with it the after screw O^2 to a position at right angles to the line of the cylinder M^2 . Then by turning the cylinder M^2 on its axis the line of travel of the after screw may be upward, downward, or laterally, at the will of the operator, the universal joint serving to revolve it in the new position. The device shown by Fig. 14 is a modification of the same arrangement. While I prefer the arrangement herein 90 described, I do not propose to confine myself strictly to the device shown in its every detail.

The main shaft R of the actuating machinery is segregated at intervals, so that one or more of the screws may be stopped or started at will; 95 but it is made continuous longitudinally from a short distance forward of the most forward side screws to the universal joint 2, connecting the after screw axle-journal with the main shaft near the stem of the vessel, down through the 100 center of the vessel parallel with and below cord C, by a series of grip-clutches, $f^1 f^2$, regulated and governed by levers f^3 .

About midships of the vessel the main shaft R is converted into a double crank, R' , through 105 which the power is carried to shaft R and the other actuating machinery from the engine. The shaft R is secured and sustained in position by bearings 21, located in brackets secured at proper intervals throughout its length. 110

On shaft R four beveled-gear wheels, $3^2 3^3$, arranged in pairs, are adjusted and secured by grip-clutches $g^1 g^2 g^3$, one to each wheel, and each clutch is handled and controlled by a lever, g^4 , by means of which the beveled wheels 115 are thrown in and out of gear. The beveled faces of each set of gear-wheels $3^2 3^3$ confront each other, and every individual wheel gears with a corresponding beveled wheel, $3'$, secured on the inner end of shaft Q , through which momentum is carried to the side screws. 120

Through shaft R the entire propulsive power is carried from the engine by the aid of the bevel-gear wheels for the side screws and universal joint for the after screw to the several 125 screws, whereby the vessel is raised, lowered, propelled, and steered; or, in other words, the side screws are geared to the main shaft R by the bevel-gear wheels $V V'$, shaft Q , and bevel-gear wheels $3'$ and $3^2 3^3$, and may be actuated or permitted to lie at rest by throwing the grip-clutch into or out of gear. 130

The axle-shaft of the after screw O^2 is connected with the main propelling-shaft R by a universal joint, 2, and may be actuated or permitted to lie at rest by throwing the grip-clutch f into or out of gear, so that one and all of the several screws may be started, stopped, run, or lie at rest at the will of the engineer.

Gearing with beveled-gear band e on the inner end of cylinders $M M'$ is a beveled-gear wheel, e' , secured on the end of shafts e^6 and e^7 , which range along on the inside of and near the sides of the vessel longitudinally, and secured respectively in journal-bearings 12 12 12 12' 12', in which they revolve, carrying at the opposite end thereof other beveled-gear wheels, e'' , which mesh with other beveled gear or miter wheels, e''' , secured on shaft e^8 , arranged horizontally at right angles to shafts e^6 , and which shaft e^8 is secured and revolves in journal-boxings 12" 12". Adjusted on shafts e^6 and e^7 are grip-clutches 13, controlled and handled by levers 13'.

In addition to the gear-wheels e''' , shaft e^8 has at one end a hand-wheel, 14, for turning the shaft in its bearings. In lieu of the hand-wheel, a crank may be used, so that the machinery can be turned by the propulsive power used to actuate the machinery. Within the bearings, near the end opposite to the hand-wheel, there is also adjusted on shaft e^8 a beveled or miter wheel, $e e$, controlled by a grip-clutch, 15, handled by a lever, 15'.

The beveled - miter wheel $e e$ gears with a beveled gear or miter wheel, $e e'$, secured on the end of shaft $e e''$, secured in bearings 12² 12².

The shaft $e e''$ runs parallel with main driving-shaft R and extends toward the rear of the vessel to cylinder M^2 , where it carries a second beveled gear or miter wheel, 11⁴, which meshes with a beveled gear or miter wheel, 11⁴', secured on a short shaft, 11'', secured in bearings and carrying at its opposite end a beveled gear or miter wheel, 11', which meshes with beveled-gear band 11 on the inner end of revolving cylinder M^2 .

It will be observed that this machinery connects the several cylinders together under one control, so that the several grip-clutches, being properly adjusted, by turning the hand-wheel 14 each and every one of the cylinders are turned in their respective bearings at one time or simultaneously, and, *per contra*, by unshipping any one or more of the series of clutches the remaining cylinders may be simultaneously revolved by this arrangement, changing the course of the vessel—that is to say, by disconnecting the after screw and turning the cylinder $M M'$ so that the screws will cut downward the vessel may be carried to the earth. By reversing them to cut upward the vessel will be carried skyward. By turning them to cut forward and again connecting the after screw the vessel will be propelled forward.

The engine 17 should be as light and compact as the state of the art will admit, and may

be of any pattern that will best serve the purpose.

17' is the smoke-stack from the boiler-furnaces. 18 is the anchor-cable winch.

The windows are of convex glass, and windows and doors are furnished with a rubber packing to exclude the air and to confine the air within the vessel when it becomes necessary to compress the air for use in high altitudes.

While I do not desire to confine myself to any specific form of vessel, the form adopted and shown in my drawings I deem to be the most practical of any.

The sharp prow and gradually-increasing lines of entrance of my vessel cause such an easy displacement that the head-resistance is barely perceptible, and the short abrupt run aft creates, as it were, a vacuum in the wake of the vessel, so that the air, rushing in to fill the vacuum formed by the moving vessel, strikes the angle of run with such force as to impel the vessel forward, exerting a force or power nearly sufficient to overcome the surface or skin friction.

19 is a wire or cord netting covering the general body of the ship.

Having now described what I esteem as my invention, what I seek to protect by Letters Patent is—

1. In a vessel for aerial navigation, constructed with a sharp long entering prow and a short abrupt after run, as shown, a gas-field involving the greater part of the area of the vessel, divided into compartments by lateral gas-tight metallic bulk-heads, substantially as shown and described.

2. Vessels for aerial navigation, constructed with a sharp long conical entering prow and a short abrupt run aft on one general frame of metal and under one cover or envelope, made air and gas tight and fire and water proof, provided with a rubber-packed gas and air tight hinge along the sides at each gunwale and on each side of the dome-ridge, said hinges forming a part of the envelope of the vessel, substantially as shown and described.

3. In combination, rubber-packed gas and air tight hinges and metal envelope or casing for vessels for aerial navigation, substantially as shown and described.

4. In combination, rubber-packed gas and air tight rubber hinges in and forming a part of vessels for aerial navigation, and revolving, raising, lowering, and propelling screws on the sides and a raising, lowering, propelling, and steering after screw, substantially as shown and described.

5. A vessel for aerial navigation, comprising a hull and a gas-field constructed on one general frame, preferably of steel tubing, inclosed with sheets of thin steel riveted and brazed together, the whole in the form of a cylinder with a long entering-cone forward and a short abrupt cone aft, having the gas-field divided into compartments by lateral metallic bulk-

heads and the hull divided into floors near the center, and the floors divided into cabin, living-rooms, freight, store, engine, and other rooms for living and business, substantially as shown, and arranged as described.

6. A vessel for aerial navigation, constructed as shown and described, inclosed within one metal cover or envelope, having rubber-packed hinges therein arranged along the sides of the vessel at the gunwales and on each side of the dome-ridge, and doors, windows, ventilators, lookout-galleries, and dead-eyes arranged in the hull portion thereof, the interior of the vessel divided into gas-field and hull, the hull divided into cabin, store, freight, engine, living, and other rooms, the whole in combination with internally-arranged propulsive machinery and externally-adjusted raising, lowering, and propelling side screws and raising, lowering, steering, and propelling after screws, substantially as shown and described.

7. In combination with gas-compartments of vessels for aerial navigation, induct gas-pipes provided with automatic as well as manual valves leading from the gas-generator and gas-reservoir, as well as educt-pipes provided with hand and automatic valves leading to the gas-receiver and to a general exhaust-pipe for inflating or collapsing any one or more of such compartments at one and the same time, substantially as shown and described.

8. Propelling after screws for vessels for aerial navigation, secured to a revolving shaft coming through from the inside and adjusted and sustained in bearings in brackets under the stern below what may be called the "stern-frame" of the vessel, substantially as shown and described.

9. In vessels for aerial navigation, constructed upon one general frame of metal, as shown, a gas-field involving the greater part of the area of the vessel, divided into compartments by lateral gas-tight metallic bulk-heads, in combination with induct-pipes provided with automatic and manual valves, and connecting with a gas-generator and gas-reservoirs, and with educt-pipes provided with automatic and manual valves and connecting with gas-condensers, and a general exhaust-pipe, passing without the vessel aft, substantially as and for the purpose shown.

10. In vessels for aerial navigation, constructed on one general frame of metal and within one cover, a gas-field involving the greater part of the area of the vessel, divided into compartments by lateral or transverse gas-tight metallic bulk-heads, in combination with rubber-packed hinges in the envelope to admit of the inflation and collapsing thereof without danger of breaking the metal, substantially as and for the purpose shown and described.

11. In vessels for aerial navigation, constructed on one general metallic frame in the form of a cylinder, with a long-drawn-out cone forward and a short cone aft and all under one

general cover, a gas-field involving the greater part of the area of the vessel, divided into compartments by gas-tight metallic lateral or transverse bulk-heads, in combination with a cabin, offices, state and other living rooms, store, engine, and other freight and business compartments internally arranged as shown, and also with passage-ways o and o' , substantially as shown and described.

12. In vessels for aerial navigation, constructed within one envelope or cover on one general metal frame in a cylindrical form with a long conic prow and an abrupt conical end aft, a gas-field involving the greater part of the area of the vessel, in combination with engine-boilers and other internally-arranged machinery for propelling, raising, lowering, and steering the vessel, substantially as shown and described.

13. In vessels for aerial navigation, constructed on one general metal frame within one cover or casing cylindrical in form, having a long conic entrance or prow and a short conic stern, a gas-field involving the greater part of the area of the vessel, in combination with propelling machinery internally arranged for actuating side screws for raising, lowering, and propelling the vessel and a screw aft for raising, lowering, steering, and propelling the vessel, substantially as shown and described.

14. In vessels for aerial navigation, constructed as shown, in combination with gas-generators, gas-condensers, and gas-reservoirs for supplying gas to the gas-field, or receiving, securing, or condensing any surplus occasioned by going into high altitudes, substantially as shown and described.

15. In vessels for aerial navigation, constructed in a cylindrical form on one metal frame, with a sharp conical prow and an abrupt conic stern within one general cover, dead-eyes in the lower part of the hull for the passage of the anchor-cables, in combination with anchor cables and winches internally arranged for hauling them in and paying them out, substantially in the manner and for the purpose described.

16. In vessels for aerial navigation, a pendulum - lever governed by a ball - weight, in combination with levers attached to collars on revolving cylinders, which carry the side screws for automatically revolving the cylinders in their bearings for keeping the vessel on a level keel, substantially as shown and described.

17. A vessel for aerial navigation, built in cylindrical form within one general envelope and on one general frame, having a long conic entrance or prow and a short conic stern, with a gas-field involving the greater part of the area of the vessel, divided into compartments by lateral or transverse gas-tight metal bulk-heads and into cabin, passage-ways, store, freight, and engine rooms within the vessel, the envelope of the vessel provided with rubber-packed hinges on the side and at dome-ridge, and actuated from within by propulsive

machinery through side and after screws, substantially as shown and described.

18. A vessel for aerial navigation, constructed in cylindrical form, with a long conic

5 entrance or prow and an abrupt conic stern on one general metal frame and within one general envelope, having a smoke-stack and steam-pipe chimney made water and fire proof and air and gas tight passing up through the gas-field, substantially as shown and described.

10 19. A vessel for aerial navigation, constructed in a cylindrical form, with a long conic prow and a short conic stern on one general frame of metal within one general envelope, having rubber-packed hinges on the sides and at the dome-ridge, as well as doors, windows, and dead-eyes in the lower part of the hull, and a smoke stack and steam-pipe chimney passing up through the gas-field, provided

15 with cabin, passage-ways, store, and freight rooms, engine and machinery compartments within the vessel, substantially as shown and described.

20 20. A vessel for aerial navigation, built on one general frame and under one cover or envelope in a cylindrical form, carried to sharp conical prow forward and a short conic stern, having one or more side screws working in revolving cylinder-shafts coming through from the inside for raising, lowering, and propelling, also provided with an adjustable shifting, lowering, raising, propelling, and steering screw-raft, working in looped stays forming part of a revolving cylinder passing through from 30 the inside sternward, substantially as shown, and for the purpose described.

35 21. Revolving cylinder-shaft M^2 , terminating at the outer end in a looped yoke, having ways in the periphery and carrying a ring, disk, or revolving carriage embedded therein, in combination with a sliding looped band secured to a collar and under control of a piston handled by a lever for changing the direction of flight of the after screw, substantially as shown and described.

40 22. Revolving cylinder-shaft M^2 , terminating at the outer end in a looped yoke, having ways in its periphery, and having a circular carriage or disk embedded in a suitable recess therein, said disk having racked teeth on a segment of its periphery to mesh with teeth on the inner edge of a sliding looped band secured to a sliding collar operated by a piston handled by a lever for changing the direction of the flight 50 of the after screw for vessels for aerial navigation, substantially as shown and described.

55 23. Revolving cylinder-shaft M^2 , terminating at the outer end in a looped yoke, having ways in its periphery, as well as a recess therein for a circular carriage provided with a sleeve journal-bearing for securing and carrying the axle of the after screw, as well as racked teeth to mesh with similar teeth on the inner side of the sliding looped band secured to a sliding collar adjusted on the revolving cylinder and operated by a piston handled by a lever for

changing the position of the after screw from right angles to a position perpendicular to the line of the cylinder, substantially as shown and described.

70 24. In combination, the after screw O^2 , journal-sleeve y' , circular carriage or disk $8'$, embedded and carried in recess 8 in the looped yoke 7 , terminating the revolving cylinder M^2 , the sliding strap-yoke or bow 6 , provided with rack-teeth 10 on the inner edge of one side, and secured to a sliding collar, 5 , adjusted on revolving cylinder M^2 and operated by a piston, 5^3 , handled by a lever, 5^4 , for handling and changing the direction of the screw O^2 , substantially as shown and described.

80 25. In combination, the after screw O^2 , journal-axle y' , universal joint 2 , actuating-shaft R , revolving cylinder M^2 , terminating in a loop-yoke, 7 , having ways in its periphery and a recess, 8 , in the interior, the circular disk or carriage $8'$, having rack-teeth $7'$ on a segment of its periphery and a sleeve journal-bearing, y , the sliding strap-yoke 6 , carrying rack-teeth 10 on the inner edge of one of the arms secured to a sliding collar, 5 , adjusted on revolving cylinder M^2 , piston 5^3 , and lever 5^4 for carrying, rotating, and changing the after screw of vessels for aerial navigation, substantially as shown and described.

90 26. A pendulum attachment consisting of a ball, S' , lever S , secured on a rocker-shaft, w^3 , carrying two lateral levers, $w^2 w^2$, secured thereto, one above and one below the rocker-shaft w^3 , the latter levers by the other ends to lever-arms $w' w'$, forming a part of collars or muffs $w w$, secured on revolving shafts $M M$, for carrying the side screws in vessels for aerial navigation, the whole adjusted near the center on the sides within the vessel, substantially as shown, and for the purpose described.

100 27. A pendulum attachment consisting of a lever, S , suspended on a rocker-shaft, w^3 , carrying a heavy ball, S' , dependent therefrom, and connected to two projecting levers, $w^2 w^2$, secured thereto, one above and one below the rocker-shaft w^3 , in combination with lever-arms $w' w'$, forming part of collars $w w$, secured on revolving cylinder $M M$ for automatically regulating the plane of flight of vessels for aerial navigation, substantially as shown and described.

110 28. A pendulum attachment consisting of a lever, S , suspended within and near the side of the vessel on a rocker-shaft, w^3 , and carrying a heavy ball, S' , dependent therefrom, and two branching levers, $w^2 w^2$, secured thereon, one above and one below the rocker-shaft w^3 , in combination with lever-arms $w' w'$, collars $w w$, secured on cylinder-shafts $M M$, which carry and change the positions of the raising, lowering, and propelling side screws, $O O$, in vessels for aerial navigation.

120 29. In combination, the main actuating-shaft R , provided with a double crank, R' , secured in journal-bearings 21 and extending longitudinally through the vessel from forward of the

cabin to the stern, segregated at intervals, but unitable by grip clutches $f' f^2$, and carrying grip-clutches $f' f^2$, grip-clutches $g' g^2 g^3$, bevel or miter gear wheels $3^2 3^3$, $3^2 3^3$, and universal 5 joint 2, axle y , and screw O^2 , in vessels for aerial navigation, substantially as shown and described.

30. In combination, main driving-shaft R , having a double crank, R' , therein, and secured 10 in bearings 21 longitudinally through the vessel, beveled or miter gear wheels $3^2 3^3$ thereon, beveled or miter gear wheels 3 on shaft Q , shaft Q , beveled or miter gear wheels $V' V$, shaft P , journaled in revolving cylinders M , and carrying 15 side screws for raising, lowering, and propelling vessels for aerial navigation, substantially as shown and described.

31. In combination, main driving-shaft R , having a double crank, R' , therein, and secured 20 in bearings 21 longitudinally through the vessel within the hull under the gas-field, and segregated at intervals, but unitable by grip-clutches $f' f^2$, carrying grip-clutches $g' g^2 g^3$, arranged for throwing beveled or miter gear 25 wheels $3^2 3^3$, $3^2 3^3$ into and out of gear, beveled gear or miter wheel 3' on the inner end of shaft Q , journaled in boxing 3 at one end, and passing through revolving shaft M , carries a miter or beveled wheel, V' , at the other, the 30 shaft Q , journal-bearings within revolving cylinder M , beveled or mitered gear-wheel V' , beveled gear or miter gear wheel V , right-angle shaft P , carrying the side screw, O , and journaled in a cross-tube head, t , on the outer end, 35 and forming part of revolving cylinder M , for raising, lowering, and propelling vessels for aerial navigation, substantially as shown and described.

32. In combination, main driving-shaft R , 40 double crank R' , bevel-gear wheels $3^2 3^3$, clutches $f' f^2$, clutches $g' g^2 g^3$, levers f^3 and g^4 , cylinder M^2 , universal joint 2, revolving carriage 8, journal-sleeve y , after screw O^2 , sliding loop-strap 6, collar 5, piston 5^3 , lever 45 5^4 , and beveled-gear wheel 3', shaft Q , beveled-gear wheel V' , beveled-gear wheel V , right-angle shaft P , side screws, O , cross-tube head t , revolving cylinder-shaft M , collar w , lever-arm w' , levers w^2 , pendulum S , ball S' , and rocker-shaft w^3 , in machinery for propelling and handling vessels for aerial navigation, substantially 50 as shown and described.

33. In combination, hand-wheel 14, shaft e^5 ,

bevel gear or miter wheels $e''' e'''$, bevel gear or miter wheels $e'' e''$, shafts $e^6 e^7$, miter or bevel gear wheels $e' e' e' e'$ on the opposite ends of shafts $e^6 e^7$, beveled or miter gear bands on the inner end of revolving shafts $M M' M M'$, revolving cylinder-shafts $M M'$, and raising, lowering, and propelling side screws, $O' O$, for simultaneously changing the position of side screws, $O' O'$, in vessels for aerial navigation, substantially as shown and described.

34. In combination, hand-wheel 14, shaft e^5 , beveled gear or miter wheel $e e$, beveled gear or miter wheel $e' e'$, shaft $e' e''$, beveled gear or miter wheels $11^4 11^3$, shaft $11''$, beveled gear or miter wheel $11'$, beveled gear or miter band 11, revolving cylinder-shaft M^2 , terminating in a loop yoke, 7, recessed for and carrying a revolving carriage, 8', journal-bearing y , after screw O^2 , axle y' , universal joint 2, main shaft R , and journal-bearings $12^2 12^2 z$, in machinery for handling, steering, and propelling vessels for aerial navigation, substantially as shown and described.

35. In combination, hand-wheel 14, shaft e^5 , beveled gear or miter wheels $e''' e'''$ thereon, beveled gear or miter wheels $e'' e''$ on shafts $e^6 e^7$, meshing therewith, longitudinal shafts $e^6 e^7$, secured in suitable bearings, beveled gear or miter wheels $e' e' e' e'$ at the opposite ends thereof, beveled gear or miter bands on the ends of revolving cylinder-shafts $M M' M' M'$, revolving shafts $M M'$, raising, lowering, and propelling side screws, $O O' O O'$, also grip-clutch 15 and bevel gear or miter wheel $e e$ on shaft e^5 , beveled gear or miter wheel $e' e'$ on shaft $e' e''$ in suitable bearings, beveled gear or miter wheels $11^4 11^3$, shaft $11''$, beveled gear or miter wheel $11'$, beveled gear or miter band 11, revolving cylinder-shaft M^2 , sliding muff or collar 5, loop straps 6, revolving carriage 8', adjustable after screw O^2 , piston 5^3 , hand-lever 5^4 , in machinery internally and externally arranged for simultaneously changing the position of the screws, both on the sides and astern, for raising, lowering, propelling, and steering vessels for aerial navigation, substantially as shown and described.

In testimony whereof I affix my signature in presence of two witnesses.

ALBERT L. BLACKMAN.

Witnesses:

B. LEWIS BLACKFORD,
PIERCE M. B. YOUNG.
